UNITED STATES PATENT OFFICE.

EDWARD BOUTON, JR., OF LOS ANGELES, CALIFORNIA.

METHOD OF AND MEANS FOR MAINTAINING INTERNAL-COMBUSTION CHAMBERS AT AN EFFICIENT TEMPERATURE.

1,226,180.

Specification of Letters Patent. Patented May 15, 1917.

Application filed May 18, 1915. Serial No. 23,841.

To all whom it may concern:

Be it known that I, EDWARD BOUTON, Jr., a citizen of the United States, residing at Los Angeles, in the county of Los Angeles and State of California, have invented a new and useful Method of and Means for Maintaining Internal-Combustion Chambers at an Efficient Temperature, of which the following is a specification.

10 In the operation of internal combustion engines it is essential for various reasons that the engine cylinder shall not become overheated, and various means have been heretofore employed for preventing such overheating. On the other hand it is found that superior economy and smoother running and greater efficiency can be secured by maintaining the engine cylinder at a sufficiently high temperature to facilitate the vaporization of 15 the fuel and the resultant combustion. So far as I am aware the only methods looking toward thus increasing the efficiency are as follows:

First, by surrounding the cylinder with a 20 hopper containing water which is evaporated by the heat of the cylinder, thus preventing the temperature from rising unduly.

Second, by surrounding the cylinder with a jacket completely filled with water which is 25 continuously circulated through the radiator to cool it.

With respect to this second system two methods of regulating the temperature of the engine cylinder have been employed, 30 viz., (a) a thermostatically controlled valve is provided to prevent undue circulation, and consequent undue cooling of the cylinder; (b) by covering part of the radiating surface to prevent undue reduction of temperature.

40 There are various difficulties arising from the use of these several methods which I wish to avoid, viz.:

With the hopper method, the escape of the 45 steam excessively lowers the water level, therefore requiring frequent attention and replenishing of the cooling medium.

With the water-circulating system, if the 50 radiator is ample to carry off all the heat on a hot day the cylinder does not reach an efficient temperature on a cold day.

With a thermostat the circulation in the radiator may be so retarded as to allow the

circulating medium to freeze in cold weather.

The covering of a part of the radiator surface to prevent undue cooling is a makeshift and requires constant attention on the part of the operator.

The object of the invention is to avoid all 60 of the foregoing difficulties and to provide for the maintenance in the internal combustion chamber of a predetermined temperature during the practical operation of the engine, and this I accomplish by applying 65 to the walls of the combustion chamber a vaporizable cooling medium thereby carrying off the undue heat from the combustion chamber by means of vapors or steam produced by such heat; collecting such vapors 70 or steam; condensing said vapors or steam, and then returning the products of condensation to the walls of the combustion chamber for a repetition of vaporization and condensing.

75 The invention includes the foregoing method and also the means by which said method is made practical.

Said means may be of various constructions and arrangements, and some of these 80 will be illustrated herein in order that the invention may be fully understood, but I do not intend to limit the invention to the particular or specific means herein shown.

The invention may be understood by reference to the accompanying drawings which are diagrammatic representations of four 85 different forms in which I at present contemplate constructing means for carrying out the invention.

90 Figure 1 is a diagrammatic elevation of an apparatus constructed in accordance with this invention and employing a pump to return the liquid of condensation from the condenser back to the water jacket of the engine cylinder.

Fig. 2 is a view analogous to Fig. 1 showing a construction similar to Fig. 1 with the difference that a pressure regulating valve is employed to increase the vaporizing 100 point of the cooling liquid.

Fig. 3 is a view analogous to Figs. 1 and 2, showing the invention applied for gravity operation at atmospheric pressure.

Fig. 4 is a view analogous to Figs. 1, 2 105 and 3 showing the apparatus constructed

for gravity operation at a pressure and temperature above that attainable in the form shown in Fig. 3.

In all the views 1 indicates the walls of the internal combustion chamber, 2 the piston therein, 3 the jacket surrounding the chamber for application of liquid cooling medium to the chamber, 4 the vapor or steam receiving space, and 5 a condenser connected with said vapor receiving space 4. 6 indicates the liquid cooling medium which is applied to the walls 1 of the combustion chamber and which is vaporized by the heat thereof during the combustive action within the chamber.

In Fig. 1 the condenser 5 is directly connected with the vapor or steam receiving chamber 4 at the upper part of the jacket 3 by means of an open escape pipe 7, and the liquid of condensation descends into a chamber 8 at the bottom of the condenser. A vent 9 is provided to prevent accumulation of pressure in said chamber 8.

A pump 10 is connected by a pipe 11 with the chamber 8 and by a pipe 12 with the cooling jacket 3 and is operated to return liquid of condensation from the condenser to the body of cooling liquid 6 in the cooling chamber 3.

In Fig. 2 the construction is the same as that shown in Fig. 1 excepting that in the escape pipe 71 a pressure-regulating valve 13 is provided, the same being constructed, as indicated by the separable weights 14 on the valve stem 15, for exerting a regulated or predetermined pressure on the contents of the vapor or steam-receiving chamber 4, thus increasing the vaporizing point of the cooling medium 6. The vapors which escape past the pressure regulating valve are condensed by the condenser 5 and returned by a pump 10 as in Fig. 1 to the cooling body in chamber 3.

The two forms shown in Figs. 1 and 2 are designed for application under those conditions where vertical space is limited, as for instance on the engines of automobiles and the like.

In Fig. 3 the condenser 5 is located sufficiently above the liquid level in the cooling chamber to allow the liquid to drain back sufficiently to avoid accumulations of liquid in the condenser. In the form shown a pipe 16 leads from the chamber 8 at the lower end of the condenser to the lower end of the cooling chamber 3. It evidently is not essential that the pipe 16 should enter at the lower end of the cooling chamber, although such construction is preferable.

The form shown in Fig. 3 is applicable to stationary engines, farm engines, and to other use where moderate head room or vertical space is available so that the condenser may be somewhat elevated.

The form shown in Fig. 4 is more particu-

larly designed for the use of engines in power plants where a considerable elevation of the condenser is possible, and is intended to utilize the force of gravity to return the liquid of condensation to the body of cooling medium in the chamber against a regulated pressure above the atmospheric pressure.

In Fig. 4 the vapor or steam space 4 is connected through a pressure regulating valve 13 with a vertical pipe 72 which may extend to an indefinite height and is connected at its upper end to the condenser 5 which is elevated as high as may be desired above the cooling chamber. The pipe 111 returns the liquid to the lower part of the cooling chamber 3 and the liquid of condensation 61 is maintained in said pipe at a height predetermined by the resistance of the pressure regulating valve 13 which is constructed after the manner described with regard to the pressure-regulating valve in Fig. 2.

In the form shown in Figs. 1 and 2 the temperature of the combustion chamber will correspond to the boiling point of the cooling liquid.

In the form shown in Figs. 2 and 4 the temperature of the combustion chamber will correspond to that indicated by the boiling point at the pressure determined by the pressure-regulating valve.

It is to be noted that in each of the views the vapors flow to the radiator 5 from the surface *a* of the cooling medium in the cooling jacket 3 around the cylinder 1 and that the products of condensation from the radiator 5 in each of the views flows to an isolated surface *b* of the products of condensation flowing from the radiator and that means such as the pipe 11, pump 10 and pipe 12 in Figs. 1 and 2 and the pipe 16 and 111 in Figs. 3 and 4 respectively operate as means to conduct the condensate from the isolated surface to the cooling jacket of the engine.

It is thus seen that in this method the only source of supply of the cooling medium is the condenser or radiator 5 from which the condensate is collected. There is, therefore, a boiling surface at *a* throwing off heat by vaporization of a portion of the cooling medium, and the resultant steam or vapor and its contained heat is all that passes to the radiator and condenser 5. The heat contained in this vapor or steam is more freely separated from such vehicle than it would be from liquid circulating through the radiator and cooler 5. The elimination of heat from the cylinder is effected by the processes of ebullition and evaporation, and the heat is finally removed from the apparatus by radiation. This is regarded as broadly new and pioneer in view of the fact that heretofore the removal of heat from the cylinder has been effected by circulating the cooling medium from the place where it re-

ceives its heat to the radiator. In this apparatus there is no circulation of the liquid cooling medium from the cylinder to the radiator.

5 It is to be noted that in all of the forms of apparatus shown, the means for returning the condensate to the cooling chamber operates simultaneously with the means for collecting, condensing and conducting the 10 products of condensation, and that the operation of the apparatus is therefore not intermittent, and may be relied upon at all times.

I claim:

15 1. The method set forth of maintaining an internal combustion chamber at efficient temperature, consisting in applying to such chamber a vaporizable body of cooling medium, collecting vapors from said medium, 20 condensing said vapors, collecting the condensate in a body having its top surface below the level of said body of cooling medium and returning the products of such condensation to said body of cooling medium.

25 2. The method set forth of maintaining an internal combustion chamber at efficient temperature, consisting in applying to such chamber a vaporizable body of cooling liquid medium, collecting vapors from said medium, condensing said vapors, collecting the condensate in a body having its top surface below the level of said body of cooling medium and returning the products of such 30 condensation to said body of cooling medium.

35 3. The method set forth of maintaining an internal combustion chamber at efficient temperature consisting in applying to such 40 chamber a body of vaporizable cooling medium, maintaining said medium and the vapors or steam therefrom at a pressure in excess of atmospheric pressure, allowing vapors or steam to escape upon undue pressure, condensing the escaping vapors or 45 steam and returning only the products of such condensation to the cooling body.

4. The method set forth of maintaining an internal combustion chamber at efficient 50 temperature consisting in applying to such chamber a body of vaporizable cooling medium, maintaining said medium and the vapors or steam therefrom at a regulated pressure in excess of atmospheric pressure, allowing vapors to escape upon undue pressure, condensing the escaping vapors or 55 steam and returning the products of condensation to the cooling body.

5. The means set forth for maintaining an internal combustion chamber at efficient 60 temperature which comprises in combination with the combustion chamber, means for applying cooling medium to the walls of said chamber, means for collecting vapors or steam from said cooling medium, means

for condensing the vapors or steam thus collected, and means for conducting the products of condensation to an isolated surface of condensate thus collected, and means for returning such condensate to the cooling 70 chamber; said condensate returning means operating simultaneously with said collecting, condensing and conducting means.

6. The means set forth for maintaining an internal combustion chamber at efficient 75 temperature which comprises, in combination with the combustion chamber, means for applying cooling medium to the walls of said chamber, means for collecting vapors or steam from said cooling medium, means for maintaining said cooling medium and the vapors or steam arising therefrom at a pre-determined pressure above atmospheric pressure, regulatable means to allow the escape of said vapors or steam at a pressure 80 above said pre-determined pressure, means for condensing the vapors or steam so escaping, and means for returning the products of condensation to the cooling chamber.

7. The means set forth for maintaining 90 an internal combustion chamber at efficient temperature which comprises, in combination with the combustion chamber, means for applying cooling medium to the walls of said chamber, means for collecting vapors or steam arising from said cooling medium, means for maintaining said cooling medium and the vapors or steam arising therefrom at a pre-determined pressure 95 above atmospheric pressure, regulatable means to allow the escape of said vapors or steam at a pressure above said predetermined pressure, means for condensing the vapors or steam so escaping, and a pump connected for returning the products of condensation to the cooling chamber.

8. The method set forth of maintaining an internal combustion chamber at efficient temperature, consisting in applying to such chamber a body of vaporizable cooling liquid 100 medium, applying to said body through the force of its own gravity a pressure in excess of atmospheric pressure, maintaining the products of vaporization arising from said body at said excess pressure, regulat- 105 ably allowing the escape of products of vaporization consequent upon undue rise of temperature, condensing the escaping products of vaporization and returning the products of condensation to the cooling body.

9. The means set forth for maintaining an internal combustion chamber at efficient 110 temperature which comprises, in combination with a combustion chamber, means for applying cooling medium to the walls of said chamber, means for collecting products of vaporization arising from said cooling medium, regulatable means for maintaining said cooling medium and the products of vaporization arising therefrom at a pre- 115 120 125 130

4
terminated pressure above atmospheric pressure, means to allow the escape of said products of vaporization at a pressure above said predetermined pressure, means elevated 5 above the level of the combustion chamber for condensing the products of vaporization so escaping, and a pipe to conduct the products of condensation to the cooling chamber.

10. The combination with a combustion chamber, of a cooling chamber to apply cooling medium to the walls of the combustion chamber, a chamber to receive the products of vaporization from the contents of the cooling chamber, a condenser connected 15 with said chamber and elevated above the cooling chamber, a pipe to conduct the products of condensation down into the cooling chamber to create a pressure therein, and

a valve to prevent the escape from the chamber of the products of vaporization at a 20 pressure below a predetermined pressure.

11. The combination with an engine cylinder, of a cooling jacket therefor, a condenser and radiator, means for conducting vapor from the surface of the cooling medium in 25 the cooling jacket to the radiator and condenser, means for collecting condensate from the radiator and condenser, and means for returning such condensate to the cooling jacket against the force of gravity. 30

In testimony whereof, I have hereunto set my hand at Los Angeles California, this 13th day of May, 1915.

EDWARD BOUTON, JR.

In presence of—
JAMES R. TOWNSEND.
